UNITED STATES PATENT OFFICE.

JOHN SHERMAN McCHESNEY, OF CHICAGO, ILLINOIS, ASSIGNOR TO J. S. McCHESNEY & CO., OF CHICAGO, ILLINOIS, A CORPORATION OF ILLINOIS.

STAPLING-MACHINE.

1,239,496.

Specification of Letters Patent. Patented Sept. 11, 1917.

Application filed February 24, 1915. Serial No. 10,369.

To all whom it may concern:

Be it known that I, JOHN SHERMAN McCHESNEY, citizen of the United States, residing at Chicago, in the county of Cook and State of Illinois, have invented a certain new and useful Improvement in Stapling-Machines, of which the following is a full, clear, concise, and exact description, reference being had to the accompanying drawings, forming a part of this specification.

My invention relates to stapling machines and is of particular service in effecting the application of staples to brooms in the process of their manufacture, though the invention is not to be limited to this use.

In practising my invention I employ a driver, an anvil, and means for effecting relative movement between the driver and anvil, the driver and anvil being provided with formations for engaging staples or stapling wire therebetween. Each staple or stapling wire portion is bent into holding relation with the work to which it is to be applied when the driver has been moved to the full extent toward the anvil.

My invention also has for its object the provision of a staple wire support, preferably a needle which operates in conjunction with the aforesaid mechanism and which serves to prepare the way for the staple and to present the staple to the work to which the staple is to be applied. Mechanism is provided whereby the needle is advanced approximately to position before the staple enters the work so that the staple cannot have its formation completed before the position in which it is to be placed with respect to the work to which it is to be applied has been fully determined. The needle also desirably operates in conjunction with the driver and anvil in bringing the staple to its final shape. Where the invention is employed in a broom making machine the anvil is desirably also in the form of a vise jaw movable toward and from a complementary jaw in which latter jaw the needle and driver are reciprocated. By this arrangement I am enabled to collapse the bundles of broom straw to the approximate shape of the brooms whereafter the staples are passed through the collapsed bundles of straw and are preferably engaged with bands that surround the brooms to keep

these bands from spreading and to maintain 55 the brooms in shape.

I will explain my invention more fully by reference to the accompanying drawings showing the preferred embodiment thereof and in which Figure 1 is a perspective view 60 of the machine made in accordance with the preferred embodiment of the invention; Fig. 2 is a view of the product resulting from the operation of the machine; Fig. 3 is a longitudinal sectional view of the upper 65 part of the machine; Figs. 4 and 5 are longitudinal sectional views, somewhat diagrammatic, of parts of the upper portion of the machine, these two views showing such parts in differing relations; Fig. 6 is a view 70 of the needle which is preferably employed; Fig. 7 is a view of a driver; and Fig. 8 illustrates an endless band which is desirably employed in forming the broom.

Like parts are indicated by similar characters of reference throughout the different figures.

The broom forming bundle of straw 1 is passed, shoulder first, through a band 2 which is preferably endless, this band being 80 formed of an iron rod welded at 3, though the form of band which is employed is immaterial to the invention. The machine includes a vise comprising a movable jaw 4 and a stationary jaw 5 which latter jaw also 85 constitutes the foundation of the machine. Two rods 6 are fixedly attached at their forward ends to the jaw 4, these rods being provided with rack formations 7 which are engaged by the teeth of supplemental gears 8 90 that are mounted upon a common shaft 9. One of these gears is provided with a handle 10 whereby the shaft 9 may be turned and both segmental gears 8 turned in unison whereby the jaw 4 may be moved back and 95 forth. The broom with the band 2 placed about the same is interposed between the jaws 4, 5 of the vise, when jaw 4 is moved outwardly, whereafter the shaft 9 is turned clockwise to press the band 2 into firm engagement with the straw of the broom, to shape the broom. One or more of such bands may be employed, though one is sufficient for certain types of brooms.

In order that the material of which the 105 bands 2 are formed may be as light as possible, the shape holding function of the band is supplemented by means of staples 11

which are passed transversely through the broom and which desirably have eye formations 11¹, 11² at their ends in which the sides of the associate band are received as indicated most clearly in Fig. 5, the broom straw being omitted from this figure as well as from Fig. 4 for the sake of clearness. After the band has been collapsed by the closure of the vise jaw 4 to the position indicated in Fig. 1, the lever 12 is turned counter-clockwise to rotate the pinion 13 which is in mesh with the rack teeth provided upon the bottom side of the rack plate 14. The rack plate 14 is therefore moved forwardly and carries with it the pawl carrier 15 which may be integrally formed with the plate 14. This pawl carrier is provided with vertical slots 16, preferably two in number, in which pawls or driving connections 17 are intermediately pivoted, the left hand ends of these pawls being the heavier in order that the pawls may normally occupy the positions illustrated in Figs. 1 and 3. When the rack plate 14 is moved forwardly, the pawls 17 will come into engagement, at their lower ends, each with a notch 18 provided in a needle 19 (which also acts as a stapling wire support), there being one such needle in association with each pawl. Each needle has a nose 19¹ at its forward end whereby the entry of this forward portion among the straw is facilitated. The pawl carrier 15 is provided with channel ways on its bottom side which are in sliding fit with the needles. These channel ways maintain the needles in fixed lines of movement and maintain the notches 18 in the same planes with the pawls 17, as illustrated most clearly in Fig. 3. The top sides of the needles 19 are provided with longitudinal channel ways 20 that lie in the same vertical planes with the vertical slots 21 in the machine foundation 5. The stapling wire portions 11 are preferably initially in the form of partially made staples as illustrated in Fig. 4 and in such form they are dropped through the slots 21 into the channel ways 20 of the needles 19 that are employed to prepare passageways for or to guide staples, the initial position of the staples within the channel ways 20 being illustrated in Fig. 4. The deposit of the staples within the channels 20 is effected before the plate 14 is moved forwardly. After such deposit has occurred the plate 14 is moved forwardly in the manner described whereupon the drivers 22, whose rear ends are rigidly secured to the forward portion of the pawl carrier 15, are pushed forwardly. These drivers have sliding fit within the channels 20 and are concaved at their forward ends, as indicated at 22¹, to receive the single bight initially formed in the staple, as indicated in Fig. 4, these cavities 22¹ taking part in forming eyes in the staples as 65 will appear. As the rack plate 14 is moved

forwardly, the pawl carrier 15 moves therewith as these two elements are of integral formation and the pawl carrier 15 pushes the drivers 22 forwardly within the channels 20 whereby the previously deposited staples 11 are moved forwardly. The unbent, forward, ends of the staples are ultimately brought into engagement with the curling bight and eye forming recesses 23 provided in the rear face of the vise jaw 4 (which jaw thus constitutes an anvil), the immediate consequence being first to form the rear eyes 11¹ in said staples and the ultimate consequence being the formation of the forward eyes 11² in such staples, these eyes embracing opposite sides of the band 2 to prevent these band sides from spreading apart, whereby such band may be made of lighter material than would otherwise be required to enable them to maintain the broom in shape. Before the drivers 22 operate, the needles 19 are desirably nearly or completely projected to their foremost positions, as illustrated in Figs. 4 and 5; in which they bridge the gap between the vise jaws 4 and 5. When the needles have thus bridged the spacing between the vise jaws the pawls 17 are disengaged from the notches 18 by having their upper ends come in contact with the pawl releaser 24, then stationary. Although the pawl releaser 24 is stationary when it functions it is maintained in fixed relation with the jaw 4 by being secured to the rods 6 as indicated in Fig. 1, whereby the pawls 17 are sure to be released when the needles 19 have been brought to their foremost position to bridge the gap between the jaws 4 and 5 whatever the width of this gap may be. Thus the jaw 4 may be moved toward the jaw 5 varying distances to suit the varying masses of broom straw interposed therebetween without changing the position of the needles with respect to the jaw 4 when the needles are in the foremost positions.

After the staples have had the eyes 11¹, 11² formed therein in the manner described the lever 12 is turned in a clockwise direction to move the rack plate 14 to the right, together with the pawl carrier 15. When the pawl carrier 15 is moved a sufficient distance to the right its rear face engages the shoulder 25 on the rear ends of the needles 19 to withdraw these needles to the position generally indicated by dotted lines in Fig. 4. Any suitable means may be employed for positioning the band 2 with respect to the needles. I have shown band or work holding chucks 21 upon the opposing faces of the jaws 4 and 5 which operate to bring the sides of the band 2 into the plane of the top of the needles whereby the staples 11 are so positioned that the eyes are sure to be formed about the sides of the band.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

- 10 1. A stapling machine including an anvil; a needle for guiding staples; a driver for moving staples along the needle; mechanism for moving the driver and the needle toward the anvil; a driving connection between said mechanism and the needle whereby the driver and the needle are initially moved toward the anvil together; means 25 operating upon said driving connection upon a predetermined advance of the needle and driver for uncoupling said mechanism and the needle to thereafter permit the driver to move alone toward the anvil; 30 chucks for holding work in position to be stapled; and mechanism for causing approach of one chuck toward the other prior to movement of the needle and driver toward the anvil.
- 15 2. A stapling machine including an anvil; a needle for guiding staples; a driver 35 and driver for uncoupling said mechanism and the needle to thereafter permit the driver to move alone toward the anvil.
- 20 2. A stapling machine including an anvil; a needle for guiding staples; a driver 40

for moving staples along the needle; mechanism for moving the driver and the needle toward the anvil; a driving connection between said mechanism and the needle whereby the driver and the needle are initially moved toward the anvil together; means 25 operating upon said driving connection upon a predetermined advance of the needle and driver for uncoupling said mechanism and the needle to thereafter permit the driver to move alone toward the anvil; 30 chucks for holding work in position to be stapled; and mechanism for causing approach of one chuck toward the other prior to movement of the needle and driver toward the anvil.

In witness whereof, I hereunto subscribe my name this sixteenth day of February A. D., 1915.

JOHN SHERMAN McCHESNEY.
